UNITED STATES PATENT OFFICE.

ALBERT HENRY FRANKS PERL AND RICHARD HEMMINGS CARTER, OF LADBROKE GROVE, LONDON, ENGLAND.

HAND-OPERATED SHEARING DEVICE.

Application filed December 10, 1923. Serial No. 679,819.

This invention relates to hand-operated cutting devices of the kind in which two operating levers are connected by links so as to obtain a variable leverage and the said invention has for its object to provide an improved hand-operated cutting device of the aforesaid kind which device is more especially intended for use in shearing and/or cutting sheet metal.

According to the present invention the device comprises two operating levers pivotally interconnected by two links angularly disposed to each other, each link having pivotal connection with each operating lever and means carried by one of the said links adapted to co-operate with the means on the adjacent operating lever to effect cutting and/or shearing on manipulation of the operating levers. The two operating levers are pivotally connected by crossed links one of the links forming a bell crank lever (hereinafter referred to as bell crank lever) which is provided with attachable and detachable means to effect cutting and/or shearing. A part of the operating lever adjacent to the said cutter on the offset portion of the bell crank lever is provided with an attachable and detachable cutter so that these two cutters on manipulation of the operating levers effect cutting and/or shearing in an extremely efficient manner. In the event of the bell crank lever becoming somewhat loose between the sides of the operating lever adjacent to the cutter on the said bell crank lever, means are provided whereby the said sides of the operating lever may be tightened on the bell crank lever.

In order that the invention may be clearly understood reference is made to the accompanying drawing which shews by way of example a construction in accordance with the present invention, but we do not limit ourselves to the precise construction herein-after described and illustrated in the accompanying drawing.

Figure 1 is a perspective view of one side of the device, and Figure 2 is a part elevation of the reverse side of the device shewn in Figure 1.

Figure 3 is a section with parts of the sides of the operating levers removed so as to shew the arrangement and disposition of the bell crank lever herein-after referred to and the co-operating parts.

Referring to the drawing the device comprises two operating levers 1, 2 pivotally interconnected by links 3, 4 angularly disposed to each other. One of the links 3, i. e. the outer link, which forms a pivoted offset from the lever 1 is provided with a cutter 5, 60 the said cutter extending forwardly of the device and outwardly of the end of the adjacent operating lever. The link 3 carrying the cutter forms a bell crank lever. The lever 2 is provided adjacent to the cutter 5 65 with a cutter 6 which is secured to the said lever 2 by screws 7 or other suitable means. The bell crank lever 3 is pivotally connected at 8 to the co-operating lever 2, the other link 4 being pivotally connected to the lever 70 2 at a point 8' forward of the pivotal connection 8 of the bell crank lever to the lever 2 and to the lever 1 as at 14.

The bell crank lever 3 may be provided with a plurality of holes 9 and the pivotal pins 8' and 9' connecting the said bell crank lever 3 to the adjacent levers 2 and 1 may be removable from their holes and may be inserted in holes 9 so as to provide for adjustment of the said bell crank lever 3 relatively to the lever 2. Holes 12 or 11 may also be provided in either the lever 1 or 2, or both levers 1 and 2, for adjustment purposes.

If so desired, the lever 1, Figure 3, which carries the bell crank lever may be provided with a number of holes 12 so that the end 13 of the interconnecting link 4 may be adjusted to any desired position within the range of the holes disposed along any desired length of the non-cutting lever 1. The operating levers 1, 2 are formed of duplicate metallic strips preferably interconnected by bolts and nuts 14 or other suitable means. The link 4 is also formed of duplicate strips 95 through and between the strips of which the bell crank lever passes, the strips of the link 4 being pivotally connected at their ends and to the levers 1, 2. The lever 2 is provided with means such as a bolt 15 and nut 100 whereby the sides of the said lever 2 can be tightened on the bell crank lever 3 if found necessary or desirable. The operating levers 1, 2 may be retained in the inoperative or non-cutting and non-shearing position by a 105 spring 16 as shewn. The outer and rear end of the cutter 6 is provided with a cutting edge as at 17 so that it may co-operate with

the adjacent edge of the cutter 5 to effect the cutting of wire and like material. The cutter 5 may be formed as an integral part of the bell crank lever 3 or the said cutter may 5 be rigidly connected to the lever by any suitable means. If so desired the outer and rear edge of the cutter 6 on the co-operating edge of the cutter 5 may be formed as straight cutting edges instead of the formation shewn 10 in the drawing, the purpose, however, being the same.

If desired, the lever 2 and also the lever 1 may be formed from a sheet metal blank doubled on itself as shewn and the interconnecting link 4 which is also preferably 15 formed of duplicate metallic strips and the bell crank lever 3 may be disposed therebetween. The forward end of the lever 2 is open at both edges as at 18 to allow of the 20 operation of the bell crank lever.

What we claim is:—

A hand-operated cutting device comprising two operating levers, crossed links pivotally interconnecting said levers to cause the operative ends thereof to diverge during cutting, one of said links extending below one of the levers with its projection having a cutter with its cutting edge projected toward and in spaced relation to the adjacent lever, and a second cutter carried removably by said adjacent lever and having its cutting edge inclined downwardly and rearwardly with respect to the lever and of a length to cross the cutting edge of the first mentioned cutter in all relative positions of the levers. 25 30 35

In testimony whereof we have hereunto signed our names.

ALBERT HENRY FRANKS PERL
RICHARD HEMMINGS CARTER.
